[57] CLAIM

The ornamental design for a parking permit holder, as shown and described.

DESCRIPTION

FIG. 1 is a front elevational view of the parking permit holder of the present invention, the rear view being a mirror image thereof;

FIG. 2 is a rear elevational view of the parking permit holder of FIG. 1, the front view being a mirror image thereof;

FIG. 3 is a top plan view of the parking permit holder of FIG. 1; and,

FIG. 4 is a bottom plan view of the parking permit holder of FIG. 1.

The surfaces of the article not shown in the drawing or described in the specification form no part of the claimed design.
